STOP MOTION

Edmund Hamel, Dahlweg 102, Munster, Germany

Filed Sept. 24, 1958, Ser. No. 762,965

Claims priority, application Germany Oct. 16, 1957

4 Claims. (Cl. 57—84)

This invention relates to improvements in twisting frames and more particularly to an individual stop motion element in operative engagement with the individual threads being twisted.

One of the objects of the present invention is to provide an individual stop motion element for each individual thread being processed in a twisting frame.

Another object of the present invention is to provide instantaneous stopping of the thread supply to a twisting spindle upon thread breakage without interfering with the operation of the other twisting spindles.

And still another object of the present invention is to provide a stop motion for a twisting frame which is more efficient in operation, less costly to manufacture and maintain and which upon thread breakage saves thread and the operative time to repair the break.

The present invention is directed to twisting frames of the type having a driving lower roller and a driven upper roller which may be placed in one of three positions on a bracket arm. One position is the temporary storage position. The second position is the inoperative or non-working position. The third position is the lower roller engagement, driven or working position. A thread is drawn between the upper and lower roller in passing from a source of supply to a twisting spindle.

According to the invention, the stop motion element is a segmental member pivotally mounted in a manner to be under the influence and control of the running thread. Upon thread breakage, the stop motion element will be subjected to movement created by its mass being eccentrically disposed with respect to its pivot. The stop motion element will engage and move the upper driven roller from drive contact with the lower driving roller and thereby cease drawing the thread from the source of supply in its passage to the twisting spindle.

Other objects of the present invention will become apparent in part and be pointed out in part in the following specification and claims.

In the accompanying drawings wherein like reference characters refer to like parts:

Figure 1 is a schematic transverse cross sectional view through a twisting frame showing the operating position or work performing condition of the several parts.

Figure 2 is a view similar to Figure 1 showing the position of the stop motion member when thread breakage occurs.

Figure 3 is a view similar to Figure 2 showing the position of the top roller after it has been lifted away from the bottom roller by the stop motion member.

Figure 4 is a schematic transverse cross sectional view, enlarged, of the stop motion member.

Figure 5 is a view similar to Figure 1 showing the construction of a modified form of thread eyelet with thread delivery through the upper eyelet.

Figure 6 is a view similar to Figure 5 with thread delivery through the lower eyelet.

Referring to the drawings, 1 designates the driven bottom roller of a conventional type twisting frame. A plurality of top rollers 2, one for each twisting spindle, are provided on opposite sides with trunnions 3. A plurality

2

of fixed rails 5 are secured to the machine frame. There are two rails 5, for and on either side of top rollers 2. Rails 5 are provided with upwardly inclined surfaces 4 having outboard lugs 6 and inboard lugs 7 terminating in the opposite ends of inclined surfaces 4. Trunnions 3 are rotatively mounted upon inclined surface 4. Rails 5 are provided with notches 8, into which the trunnions 3 are manually positioned when an upper roller 2 is placed in storage position.

10 Top rollers 2 when positioned on inclined surfaces 4 at lugs 6 engage and are frictionally driven by bottom roller 1. Surfaces 4 are inclined so that top rollers 2 are out of driven engagement with bottom roller 1 when trunnions 3 abut lugs 7. The rollers 1 and 2 rotate in the direction of the arrows shown in Figures 1, 2, 5 and 6.

A thread guide 10 having a double eyelet is fixed in the frame of the machine. There is one thread guide 10 for each upper roller 2. A rod termed a guide stem 11 extends the full length of the machine and is secured on opposite ends in the machine frame.

20 A shaft 12 extends the full length of the machine and is rotatively mounted in the machine frame. A plurality of stop motion segments 13 are loosely mounted on shafts 12 in parallel alignment with top rollers 2 and thread guides 10. There is one stop motion segment 13 for each top roller 2.

Stop motion segments 13 are mounted to freely rotate or pivot upon shaft 12. Each stop motion segment 13 is mounted with its mass eccentrically disposed with respect to its pivot on shaft 12.

30 Each stop motion segment 13 is provided with a coating of friction creating material, such as rubber, on its segmental periphery 15 for purposes which will presently appear.

35 A plurality of clips 16 are fixed to shaft 12. Stop motion segments 13 are undercut as at 20 so as to house clips 16. Clips 16 prevent stop motion segments 13 from longitudinally sliding along shaft 12. Each stop motion segment 13 is provided with a thread guide 14 which hereinafter will be termed the second thread guide.

40 In operation, a thread or threads 9 coming from a source of supply (not shown) passes through one of the double eyes of thread guide 10. The thread then passes to top roller 2 and partially around top roller 2 so as to pass between top roller 2 and bottom roller 3, back to the other eye of double eyed thread guide 10. Thread 9 then passes to and partially around guide stem 11, through second thread guide 14 to the twisting spindle (not shown).

45 Each stop motion segment 13, as shown in Figure 1, is held against guide stem 11 by means of the tension on thread 9 passing from guide stem 11, through second thread guide 14 to the twisting spindle. Figure 1 therefore, depicts what might be termed the loaded position of stop motion segment 13.

50 Upon the breakage of thread 9, the effect of the tension of thread 9 upon second thread guide 14 is lost. Instantaneously stop motion segment 13, unloads or pivots upon shaft 12, gaining momentum as it pivots, falls or swings toward upper roller 2, so that stop motion segment 13 has enough momentum or force upon contacting upper roller 2 to cause trunnions 3 to roll along inclined surface 4 (downwardly) from a position abutting outboard lug 6 to a position abutting inboard lug 7 and thereby cause upper roller 2 to disengage lower roller 1. The force of rotation of lower roller 1 will assist in moving upper roller 2 out of contact or engagement as the center of upper roller 2 passes the center of lower roller 1 in moving from lug 6 to lug 7. The instant upper roller 2 disengages lower roller 1, thread 9 is no longer drawn away from its source of supply.

55 The frictional coating 15 on the periphery of stop motion segment 13

provides a better contact between said stop motion segment 13 and upper roller 2.

The broken thread 9 may be tied or otherwise repaired. Stop motion segment 13 will manually be placed in loaded position as shown in Figure 1.

At the end of a working day when the twisting frame is to be stopped, shaft 12 may be rotated thereby rotating clips 16, see Figure 4, from the full line to the dotted line position. As the twisting spindles come to a halt, the tension on thread 9 ceases and stop motion segment 13 tends to unload, as previously described. However, clips 16 will abut edges 21 provided at the base of undercuts 20, so that stop motion segments 13 are maintained in loaded position even though the tension on threads 9 ceases to exist.

Figure 5 and 6 depict a modified form of thread guide. Thread guide 10 is provided with a second thread guide eye 10'. The thread 9 passes through thread guide eye 10' so as to be directed to the bottom of lower roller 1. The thread engages the left hand surface (as viewed in Figure 6) of lower roller 1 and then passes between rollers 1 and 2 and around the right hand surface (as viewed in Figure 6) of upper roller 2 to the top of upper roller 2. From the top of upper roller 2 the thread passes to guide stem 11, second thread guide 14 and the twisting spindle (not shown).

The method of operation of stop motion segments 13 is identical to all figures illustrated regardless of the manner in which thread 9 engages the upper and lower rollers 2 and 1 respectively.

Having shown and described preferred embodiments of the present invention, by way of example, but realizing that structural changes could be made and other examples given without departing from either the spirit or scope of this invention, what I claim is:

1. In a twisting frame of the type having a driving lower roller and an upper slidably mounted driven roller in driven contact with said driving lower roller, and a first thread guide fixed in the frame, that improvement in a stop motion consisting of a stop motion segment mounted for segmental rotation eccentrically with respect to its mass of weight and provided with an eyelet, horizontal in normal thread guiding operating position, so that a thread to be twisted passes through said first thread guide and around said driven roller, back to said thread guide and then to said driven roller and over said stop motion segment and through said second mentioned thread guide, said thread holding said stop motion segment in counterbalanced position against its eccentrically loaded pivoted condition, whereby upon thread breakage said stop motion segment pivots to abut said driven roller to move said roller from its position in operating contact with said driving roller to a position away from contact with said driving roller, thereby to stop said thread from feeding.

2. In a twisting frame of the type having a driving lower roller extending the full length of the frame, a plurality of top rollers, each having trunnions projecting from opposite sides, a plurality of fixed rails, two for each top roller, one on either side, fixed in the frame, each rail having an outboard lug and an inboard lug, with an inclined surface inclining from said outboard lug toward said inboard lug, said top rollers mounted for rotation through contact with said driving lower roller and said trunnions upon said inclined surface, a plurality of thread guides fixed in said frame, one thread guide in parallel alignment with a co-operating top roller, a guide stem extending the full length of the machine and secured in the frame, that improvement in a stop motion consisting of a shaft extending the full length of the frame and rotatively secured in the frame, a plurality of stop motion segments, each provided with a second thread guide, one stop motion segment for each top roller, mounted on said shaft in parallel alignment with the co-operating top roller and thread guide and mounted for segmental rotation eccentrically with respect to its mass of weight so

that a thread to be twisted passes through said first thread guide and between said top roller and said lower roller and then over said guide stem and through said second thread guide, holding said stop motion segment in a counterbalanced position against its eccentrically loaded

5 pivoted condition against said guide stem through the tension of the thread on said second thread guide, whereby upon thread breakage, said stop motion segment pivots to abut said driven top roller to move said roller from its position in operating contact with said lower driving roller to a position away from contact with said lower driving roller, thereby stop said thread from feeding, said outboard lugs defining the position of working engagement of said top rollers with said lower roller and said inboard lugs defining the position of rest for said top rollers.

3. A claim is defined in claim 2 being further characterized in that a plurality of clips are secured to said shaft on opposite sides of each top roller to prevent side-to-side movement of each stop motion segment, each stop motion segment having an undercut to provide an abutting edge whereby upon rotation of said shaft and clips said abutting edge will engage said clip to retain said stop motion segment in counterbalanced position upon loss of tension in said thread being twisted.

4. In a twisting frame of the type having a driving lower roller extending the full length of the frame, a plurality of top rollers, each having trunnions projecting from opposite sides, a plurality of fixed rails, two for each top roller, one on either side, fixed in the frame, each rail having an outboard lug defining the operative position of said top roller and an inboard lug defining the inoperative position of said top roller, with an inclined surface, inclining from said outboard lug toward said inboard lug, said top rollers in operative position engaging to be driven by said driving lower roller with said trunnions rotating along said inclined surface from operative position against said outboard lug to inoperative position against said inboard lug, that improvement in a stop motion consisting of a plurality of first thread guides fixed in the frame, one thread guide for each top roller, a guide stem extending the full length of the frame and fixed in the frame, a shaft extending the full length of the frame and rotatively secured in the frame, a plurality of stop motion segments, each provided with a second thread guide horizontal in normal operating position, one stop motion segment for each top roller, each stop motion segment mounted on said shaft in parallel alignment with the co-operating top roller and provided with a coating of friction creating material on the top roller contact surface of the segment, each stop motion segment mounted on said shaft for segmental rotation eccentrically with respect to its mass of weight so that a thread to be twisted passes through said first thread guide to and between said top and lower rollers to be drawn thereby, passes over said guide stem and through said second thread guide to retain said second thread guide in horizontal position and said segment against said guide stem to hold said stop motion segment in counterbalanced position against its eccentrically loaded pivoted condition, whereby upon thread breakage, said stop motion segment pivots to abut said top driven roller with a force of gravity through said friction coated surface to move said top roller out of engagement with said lower driving roller and through said force of gravity, said inclined surface and the direction of rotation of said lower driving roller, move said top roller to an inoperative position along said inclined surface abutting said inboard lug, thereby to stop drawing said thread between said top and lower roller.
